UNITED STATES PATENT OFFICE.

ADDISON R. DE PASS, OF COLUMBIA, SOUTH CAROLINA.

METHOD OF PROTECTING DENTAL WORK.

1,035,950.

Specification of Letters Patent. Patented Aug. 20, 1912.

Application filed June 24, 1911. Serial No. 635,233.

To all whom it may concern:

Be it known that I, ADDISON R. DE PASS, a citizen of the United States, and resident of Columbia, in the county of Richland, 5 State of South Carolina, have invented certain new and useful Improvements in Methods of Protecting Dental Work, of which the following is a specification.

This invention has for its object the protection of dental work in the mouth of a patient.

It is a well known fact that fillings and other dental work should be protected from moisture in the mouth of the patient for a 15 certain period of time after the work is done and various means have been used by dentists for this purpose. The patient has been required to keep his mouth open and cotton has been stuffed around the teeth to protect 20 them from saliva, and in addition a rubber sheet or dam is often kept around the tooth. In spite of these precautions, however, it is not always possible to prevent the access of moisture to the work.

25 My present invention is designed to effectively and absolutely protect the work from moisture, and in addition to this to avoid in a great measure the discomfort to the patient incident to the method and means 30 heretofore used and to reduce to a minimum the exertion on the part of the dentist in protecting the work.

The novel features of the invention will be apparent from the following description 35 taken in connection with the drawings.

I have illustrated a series of forms or molds for use in carrying out my invention, and these are made the subject of the claims in my divisional application No. 649,334 40 filed September 14, 1911.

In the drawings: Figure 1 is a perspective view of a form or mold adapted to fit over the upper front row of teeth; Fig. 2 shows a similar form adapted to fit over the lower front row of teeth; Fig. 3 is a similar view of a form adapted to fit over the upper right row of teeth; Fig. 4 shows a similar but shorter form adapted to fit over a section of the upper left row of teeth; Fig. 5 shows a 45 similar form adapted for use on the lower right row of teeth; and Fig. 6 is a cross sectional view showing the details of construc- 50

tion which may be used in making the mold, and in addition showing the device applied to the teeth as in actual use.

55 In carrying out my invention I cover the teeth upon which the work has been done with a mold or casting of plastic material held in a form so shaped as to properly and conveniently fit over the section of the teeth 60 in which the work has been done. The form itself does not come in contact with the teeth, but extends along both sides of the teeth up to a point beyond the exposed portions so that the teeth may sink down in the 65 form and in the plastic material contained in the form until that plastic material closely fits around the teeth and up to the gums of the patient. Plaster of Paris is a suitable material for use as the plastic material in which the teeth are embedded, but it will be understood that any other similar or suitable material may be used. When I 70 make use of plaster of Paris I preferably place sufficient material in the form to fill it 75 and then spread a thin sheet of elastic rubber over the plaster of Paris and press the form up firmly against the teeth until the teeth are embedded in the plaster of Paris with the layer of rubber between the teeth and the 80 plaster of Paris, thus effectively protecting the teeth even from the moisture contained in the plastic material. It will, of course, be understood that the plaster of Paris is moistened and in plastic form when the teeth are 85 embedded, but that it will quickly set forming a rigid cast around the teeth effectively protecting them and keeping out moisture.

The forms are so shaped that they will properly fit the various parts of the mouth with 90 as little inconvenience to the patient as possible. When it is desired to remove the cast from the teeth the mold may be first withdrawn from the cast and the plaster of Paris is then broken up and removed in sections. 95 It will be understood however that there is sufficient give in the material to permit the mold to be withdrawn from the teeth while the plaster of Paris form is in it.

100 As shown in Fig. 1 of the drawing, the mold for the upper front row of teeth has a wall 1 shaped to fit around the outside of the teeth and to extend upwardly beyond the exposed portions and there is also an inner

wall 2 fitting around the inside of the row of teeth. There is between these two walls a groove or recess which is to be filled with the plaster of Paris and covered with a thin 5 coating of water-proof material, such as rubber. The mold for the lower front row of teeth is formed with the front wall 3 and the rear wall 4 leaving a groove for the teeth between them and as shown in this figure the 10 upright walls are preferably undercut along their inner upper edges as shown at 5 so that the upper edges make a slightly contracted outlet for the material contained in the form serving to securely and firmly hold 15 it in position. I preferably make use of this undercut arrangement on each of the forms since it not only holds them in position, but makes the plastic material more firmly press against the teeth when they sink into it up 20 around the roots so as to make a close watertight joint.

In Fig. 3 I have shown a form of mold embodying the side walls 6 and 7 and a rear end wall 8 of such shape that it can be fitted 25 over the entire row of teeth on the upper right hand side. It has on its forward end on one side an outlet or opening 9 for the passage of the front teeth. It will be understood that a similar mold with the parts 30 reversed may be used for the upper left hand row of teeth.

In Fig. 4 I have shown a shorter form for the upper left hand row of teeth having the inner wall 10 and the outer wall 11 so 35 curved and shaped as to properly fit over a section of the teeth, but in this instance the form is made shorter than that indicated in Fig. 3 so that it will cover only a portion of the teeth on one side, and it will 40 consequently not be so much in the way of the patient as will the long form covering the entire row. In this particular form the ends are open except that there are upwardly bent or extending portions 12 and 13 45 serving as ribs or dams to assist in holding the material in the form while the teeth are being embedded. It will be understood that the form for the upper right side will be similarly constructed so as to fit on that side.

50 The form shown in Fig. 5 has an outer side wall 14 and an inner side wall 15 and like that shown in Fig. 4 is provided with open ends with the upward projections 16, 17 to hold the material in place.

55 Each of the forms used in carrying out my invention may be made of any suitable material such as rubber or metal. When made of rubber or similar material the side walls 60 may have sufficient resiliency to permit the form to be withdrawn from the hardened plaster of Paris notwithstanding the fact that the form may have its side walls slightly contracted toward the top. Instead of making the forms with the resilient sides, 65 however, I may make them of more rigid

material and in that case I prefer to make them in sections as indicated in Fig. 6, whereby they may be divided to release the hardened plastic material. As shown in Fig. 6, the form is made up of two longitudinal metal sections 18 and 19 divided longitudinally at the bottom, the two sections overlapping or fitting together and being held by screws or bolts 20. The bolts may pass through slots in the overlapping 70 portion so that when screwed tight they will hold the two sections firmly together forming a proper mold, but when the bolts are released the sections may be separated and removed from the material contained 75 in the form. As shown in Fig. 6 the side walls are inclined slightly toward each other at the top and have the undercut portions 5 so as to firmly hold the plaster of Paris, wax or other materials 21 and to make that 80 material fit closely around the teeth 22 when they are embedded in it. The thin sheet of rubber 23 is placed across the top of the plastic material and when the teeth are embedded in that material the rubber sheet will 85 be pressed closely around the teeth and up around the gums so as to form a tight fit, effectively keeping out any moisture. The rubber is not only water-proof, but is elastic and consequently will make a perfectly 90 water-tight joint. As shown in this figure, 95 24 represents a filling which is being protected by the plastic material and rubber coating.

I prefer to use plaster of Paris in carrying out my invention, but it will be understood that other materials may be used and this is true also of the water-proof lining or coating over the tooth when it is embedded in the plastic material which is preferably 105 of rubber, although my invention is not limited to the use of that material.

Having thus described my invention what I claim as new and desire to secure by Letters-Patent is:

1. The method of protecting dental work from saliva and moisture consisting in applying to the tooth on which the work has been done a thin flexible water-proof covering and embedding said tooth and covering 115 in a plastic mold closely fitting around said tooth to keep out moisture.

2. The method of protecting dental work from saliva and moisture consisting in covering a mass of plastic material with a thin 120 sheet of elastic rubber and pressing said material covered with said rubber around the tooth upon which the work has been done forming a closely fitting water-proof protecting covering for said tooth.

3. The method of protecting dental work from saliva and moisture consisting in covering a mass of wet plaster of Paris with a thin sheet of elastic rubber and pressing said plaster of Paris against said sheet 130

around the tooth operated on forming a closely fitting water-proof protecting covering for said tooth.

4. The method of protecting dental work from saliva and moisture consisting in filling with plastic material an open top form shaped to fit the row of teeth worked upon, covering said material with a thin water-proof elastic sheet, pressing said form

against said teeth until they are embedded 10 in said material.

In testimony whereof I affix my signature in presence of two witnesses.
